UNITED STATES PATENT OFFICE

LAWRENCE D. BALE, OF CLEVELAND, OHIO, ASSIGNOR TO UNION METAL MANUFACTURING COMPANY, OF CANTON, OHIO, A CORPORATION OF OHIO

ANCHORAGE FOR POLES

Application filed April 26, 1929. Serial No. 358,279.

The invention relates to anchorages, foundations or footings for metal poles which are used as posts, columns, or lighting standards, or as telephone, telegraph, transmission, distribution, or trolley wire suspension poles or 5 the like; and it relates more particularly to a type of anchorage, foundation or footing which is located underground, which is imbedded in concrete, and to which the standard or pole may be firmly or positively secured.

Tubular poles of this character are coming into extended use, more particularly in the larger cities, not only for lighting the city 15 streets at night, but also for supporting telephone, telegraph, transmission, distribution and trolley wires, and for other purposes. These poles are not necessarily used for only 20 one of such purposes, but one pole may carry lighting fixtures, telephone, telegraph, transmission and distribution cross bars, and trolley wire suspension means.

Thus the length or height of such a pole 25 may be forty or more feet, so that the pole will have sufficient strength to withstand the loadings and strains imposed upon it, and consequently the weight of the pole is often times very great.

The weight of the pole, and the loading and 30 strains imposed thereon, are transmitted to and carried by the anchorage, foundation, footing or underground base which must be of proper design and sufficient size to withstand the loading, and to transmit the strains 35 imposed upon the pole to the ground, without displacement of the pole or anchorage.

In the past, the underground anchorage or 40 foundation has usually consisted of a concrete block, rectangular or circular in cross section, having a depth of six or more feet and having at certain points a diameter or maximum dimension in cross section of three to five feet. A plurality of anchor rods are imbedded in the concrete block which project from 45 the top thereof, and a flange at the lower end of the pole is attached to the projecting ends of such anchor rods.

The dimensions of the present type of 50 foundation must be such that its size, weight, and strength prevent the load transmitted to

it from the pole from rupturing the concrete, and prevent the foundation from shifting in the earth. This latter condition is taken care of by the bulk and dead weight of the foundation.

The cost of setting such anchorages or 55 foundations is commonly from thirty to one hundred or more dollars depending upon specific conditions.

These poles are usually located along the 60 sidewalks of city streets at spaced intervals adjacent the curb. Thus in excavating for setting one of the above usual types of foundations, gas mains, water mains, sewers and wire tunnels are often encountered.

In many of our cities adequate records are 65 not on file giving the location of such gas mains, water mains, sewers and wire tunnels so that after an excavation has been made it may be found that there is only ten or twelve 70 inches horizontally between such mains or tunnels rather than the three to five feet required for the pole foundation.

For these reasons the installation of the anchorages for the poles is often times extremely costly and may necessitate a realignment of the whole pole system, or an elaborate and costly special design of anchorage, or a relocation of the interfering mains or tunnels.

Moreover, such usual foundations have anchor rod ends projecting upward therefrom above the surface of the sidewalk, which necessitates the use of barricades, watchmen and danger signals to prevent injuries to 75 passers-by. In most cases the poles are 80 erected and owned by utility companies, thus furnishing an easy mark for unscrupulous persons who intently injure themselves on the barricades or projecting anchor rods for the express purpose of filing damage suits 85 against the utility companies to collect damages for injuries sustained.

Furthermore, sidewalks on modern streets 90 are usually paved with slabs of concrete marked off in five foot squares, and city ordinances provide, if any part of such a square is 95 injured or damaged, that the whole square must be replaced.

Thus when an ordinary underground concrete block foundation is provided for such 100

poles, many times the excavation for the foundation injures or undermines two or more squares which causes an added cost of replacement to be reckoned into the cost of the foundation.

5 And finally, because of the damage suit hazard, utility companies only put in foundations at the present time when the poles are immediately thereafter to be mounted thereon. Thus, the utility companies are unable to anticipate future settings of poles by setting pole anchorages at a time when streets or sidewalks are being constructed, repaired, or re-paved, or when bridges are being built, 10 at which time the cost of placing the foundations would be materially less than afterwards.

15 An object of the present invention is therefore to provide an underground anchorage for a pole which may be extended into the ground below a sidewalk substantially without regard to the location of existing water mains, gas mains, sewers or wire tunnels; an anchorage which presents a flush surface with 20 the ground and an anchorage which costs materially less than the type of foundations now in use.

25 A further object of the invention is to provide an anchorage which may be buried in the ground at the site of a proposed location of a pole in anticipation of placing a pole on the site at some future time, without presenting a hazard to passers-by.

30 A further object of the present invention is to provide an anchorage, the connection between such anchorage and a pole secured thereon being removable when damaged without tearing up the anchorage from the ground.

35 40 And finally, it is an object of the present invention to provide an anchorage in which the loads transmitted to it from the pole are carried entirely by the anchorage and not by the concrete surrounding the same; the concrete acting merely as a means of increasing 45 the anchorage bearing surface. Thus the concrete does not need to be of as high a grade as is necessary in the present type of foundation, and the concrete may even be 50 poured in freezing weather without taking precautions to prevent freezing thereof.

55 These and other objects may be attained by use of an anchorage construction herein-after set forth in detail, and which may be 60 stated in general terms to include an anchoring stub, a flange or flanges located adjacent one end of said stub, the stub and flange being buried underground and preferably surrounded by concrete and presenting a flush 65 surface with the top of the ground, and means for attaching a pole to the anchorage, the greatest cross sectional dimension of the anchoring stub being less than the greatest cross sectional dimension of the pole anchored 70 thereby.

A preferred embodiment of the invention is illustrated in the accompanying drawings, in which

75 Figure 1 is a side elevation of a pole attached to the new and improved anchorage shown in position in the ground, parts of a sidewalk, curb, street and sundry pipes being shown in cross section as on the line 1—1, Fig. 3;

Fig. 2, an elevation of the pole showing the 78 ground in cross section as on the line 2—2, Fig. 3;

Fig. 3, a fragmentary plan view of a sidewalk, curb and street showing a pole in cross section as on the line 3—3, Figs. 1 and 2;

80 Fig. 4, a side elevation of the improved anchorage;

Fig. 5, an end elevation of the improved anchorage;

Fig. 6, a top plan view of the improved 85 anchorage; and

Fig. 7, a side elevation of a modified form of anchorage.

90 Similar numerals refer to similar parts throughout the drawings.

The improved anchorage generally indicated at A may consist of the anchoring stub 10, which is preferably a standard H-beam section having the required strength for resisting the strains and loads imposed upon it, as a column and beam. The form of the stub 10 need not necessarily be that of an H-beam, but may be any standard shape or shapes. However, an H-beam is preferable since the 95 outside dimensions thereof in cross section are substantially that of a square so that for a given strength, the maximum cross sectional dimension is a minimum.

100 At one end portion of the stub 10 there is attached, preferably by welding as at 11 and 105 12, a flange member or members 13, which are shown as being standard channel shapes.

110 When the flange member 13 at the top of the stub 10 is a channel shape as shown in the drawings, there may be provided between the flanges thereof a plurality of spaced tubular lengths or strut members 14 which may be welded to the flanges of the channel member 13 as at 15.

115 The central bore 16 of the tubular length 14 may be aligned with suitable holes 17 in the flanges of the channel members 13, and the holes 17 and central bore 16 may be threaded as shown in dotted lines at 18 in Fig. 4. Stud bolts 19 may be screwed into 120 the lower end of the threaded bore 18 for preventing the bore from becoming filled with concrete when the anchorage is imbedded in concrete and for tying the flanges 125 of the channel member to the tubular length.

130 The position of the ground line when the anchorage is imbedded in the ground is shown at 20 in Figs. 4 and 5 and it is seen that the anchorage has substantially a flush surface with the ground.

Figs. 1 and 2 show a pole 21 firmly secured to the anchorage A by stud bolts 22 which pass through holes 23a in a flange member 23 provided at the lower end of the pole and engage in the threaded bores 18 of the tubular sections 14.

The pole 21, the extent of the length of which is not shown, is shown as carrying a street sign 24, trolley wire suspension means 25 and cross bars 26 which may be provided with insulators 27 for suspending telephone, telegraph, transmission or distribution wires 28.

Fig. 3 shows that the base 23 of the pole 21 is secured to the anchorage A by bolts 22 at four different places. For this reason, the relative location of the holes 17 in the flange members must be the same as the relative location of the holes 23a in the flange of the base 23 through which the bolts 22 pass.

The stub 10 of the anchorage A is shown in Figs. 1 and 2 as extending into the ground for example six feet when the pole 21 has a maximum diameter D of thirteen inches and a length or height of forty or more feet. In such a case the external side cross sectional dimensions X and Y of the H-beam stub 10 are approximately eight inches.

The H-beam stub 10 is shown as positioned between a gas main 29 and a water main 30 on one side, and a sewer pipe 31 on the other side thereof.

In setting the anchorage in the ground, it is required to excavate a hole 32 therein having a diameter substantially equal to the diameter of the pole base 23, which may be under the present example, approximately twenty inches. The anchorage is then located in position between any existing gas mains, water mains or sewers 29, 30 and 31, and concrete 33 is filled in the hole 32 around the anchorage.

Shields 34 are provided usually partially surrounding the gas mains, water mains or sewers for preventing the same from being permanently imbedded in concrete which would materially hamper the subsequent removal of the same.

Thus a pole anchorage may be set in the ground at the desired position when sidewalks 35, curbs 36 and street paving 37 is being provided or renewed, and the anchorage will be flush with the surface of the sidewalk as shown in Figs. 1 and 2; and to which may be readily attached at any time the pole 21 simply by placing the base 23 on the anchorage and drawing up four bolts 22.

Since the diameter of the excavated hole is relatively small and entirely covered by the pole base, it will be rarely necessary to replace a slab or more than one slab 35a of the sidewalk 35 in setting an anchorage after the sidewalk has already been laid, as well shown in Fig. 3 of the drawings.

Moreover, the controlling dimension of the

anchorage is a side dimension X or Y of the anchoring stub 10 which under the present example is eight inches, and the anchorage may therefore be set in the ground at any place without changing or removing gas mains, water mains or sewer pipes if the horizontal space between such gas mains, water mains, or sewer pipe is eight inches or greater.

Thus the stub 10 has a side dimension X or Y of eight inches which is materially less than the largest dimension D of the pole 21, which in the present case is thirteen inches. This fact is exactly the opposite from the facts present in the common type of concrete block anchor bolt foundation now in use.

The cost of making and erecting or setting an anchorage such as disclosed herein is never more than twenty-five dollars as compared with the cost of present types of foundations for similar poles above set forth, so that many more poles of the type described may be used by cities or utility companies than are at present in use.

Moreover, should a moving object strike one of the poles, the bolts 22 would fail in tension and the same may be readily renewed simply by drilling out the severed bolt ends from the threaded bores 18, rethreading the bores, and screwing in new bolts 22. An accident to the pole would therefore necessitate the expenditure only of a small sum of money to correct the damage sustained.

Under the present form of concrete block and anchor bolt construction, should a moving object strike the pole, one or more of the anchor bolts would fail in tension and in order to repair the same the whole concrete block must be removed and a new foundation constructed which would cost substantially the same as the original foundation.

Fig. 7 shows a modified form of anchorage generally indicated at AA and may consist of the anchoring stub 100 which may be tubular; and at one end portion there is attached, preferably by welding as at 101, a cast flange member 102.

A pole indicated by dotted lines at 103 may be attached to the flange member as by the stud bolts shown in dotted lines at 104 engaging in threaded bores 105 of the flange member.

In the claims appended hereto, the word "pole" is understood to mean a pole, column, shaft, standard, or post, or any member or structure for which the anchorage is provided.

I claim:

1. An anchorage for a pole and the like including an anchoring stub, channel members attached to the upper end of said stub, tubular sections extending between the flanges of said channel members, the tubular sections providing means for connection with pole attaching means, and any cross sectional

dimension of said stub being less than the greatest cross sectional dimension of the pole attached thereto.

2. An anchorage for a pole and the like including an anchoring stub, channel members attached to the upper end of said stub, tubular sections extending between the flanges of said channel members, and the tubular sections providing means for connection with pole attaching means.

10 3. An anchorage for a pole and the like including an anchoring stub, channel members attached to the upper end of said stub, strut members extending between and connected with the flanges of said channel members, and said strut members providing means for connection with pole attaching means.

15 4. An anchorage for a pole and the like including a longitudinally extending anchoring stub, channel members attached to the upper end of said stub, and strut members located substantially parallel with the longitudinal axis of the stub extending between and engaging both flanges of said channel members providing means for connection with pole attaching means.

25 In testimony that I claim the above, I have hereunto subscribed my name.

LAWRENCE D. BALE.

CERTIFICATE OF CORRECTION.

Patent No. 1,784,568.

Granted December 9, 1930, to

LAWRENCE D. BALE.

It is hereby certified that the assignee in the above numbered patent was erroneously described and specified as "Union Metal Manufacturing Company", whereas said assignee should have been described and specified as The Union Metal Manufacturing Company, as shown by the records of assignments in this office; and that the said Letters Patent should be read with this correction therein that the same may conform to the record of the case in the Patent Office.

Signed and sealed this 13th day of January, A. D. 1931.
